UNITED STATES PATENT OFFICE.

JOSEPH ROBINSON, OF NEW YORK, N. Y.

AUTOMATIC TRAIN-PIPE CONNECTER.

Application filed April 9, 1921, Serial No. 459,926. Renewed November 10, 1926.

My invention relates to automatic train pipe connectors and has among its objects to provide a simple and efficient means for replacing defective gaskets between the faces 5 of mated connector heads while the cars equipped therewith remain coupled. Another object is to provide means to permit the connector head and buffer spring to be removed from the bracket of the automatic 10 connector while the cars remain coupled and without disassembling the spring with respect to the head.

With these and other objects in view, which will appear as the description proceeds, my invention resides in the combinations, arrangements and constructions hereinafter described, pointed out in the appended claims and illustrated in the accompanying drawings in which:

20 Figure 1 is a side elevation of an automatic connector provided with my improvement.

Figure 2 is a plan view thereof with the coupling head B omitted, and showing some 25 of the parts in section.

Figure 3 is a sectional elevation of my improved connector. In this view the coupling head B is omitted and the forward end of the pipe A, and the upper portion of the 30 bracket D, are broken away.

Figure 4 is a rear view of the structure shown in Figure 1, with the coupling head omitted and the upper part of the bracket broken away, and

35 Figure 5 is a rear view on the line 5—5 of Figure 3. In this view the coupling head is omitted and the top of the bracket is broken away.

Referring now to the drawings: My improvement comprises a pipe or body A suitably connected to any desired form of coupling head B. I preferably form the body with a laterally diverging nipple or conduit 6 at its forward end, the nipple being threaded at 7 to receive the head and at 8 to receive the usual train pipe hose 9, Figure 2, as by a union 10. Extending rearwardly from, and preferably formed integral with, the nipple 6 I provide the body A with a 50 pair of horizontally extending straps or members 11 and 12 spaced apart as shown. At their rear end the straps are suitably attached to or terminate in a vertically extending flange or projection 13 perforated 55 at 14, and having an annular seat 15 for a

spring—see Figure 3. Attached to the usual lug 16 of the car coupler C, as by bolts 17, I provide a bracket D the lower end of which terminates in a vertically extending cylindrically shaped projection or anchor device 60 18 which projects from above into the opening 19 between the straps 11 and 12, and in front of the flange 13, and normally rests thereat midway between the straps. The bracket D is provided with a web or rib 65 which projects to either side of the anchor device 18 forming projections 20 and 21 which overhang the straps 11 and 12, as appears especially in Figure 5. The projections lie directly above the point about which 70 the connector fulcrums on the bracket D and preferably in the vertical plane of the fulcrum point—see Figure 1. These projections co-operate with the straps 11 and 12 to prevent excessive rotation of the body A 75 and the coupling head B about the longitudinal axis of the body.

Formed on the projection 18, preferably midway the width of the straps 11 and 12, I provide a curved or flaring seat or bearing 80 22 having overhanging portions 23 and 24, and extending from the rear of the flange 13, through the perforation 14 therein, I provide a tie rod or pivot device 25 having at its forward end a perforated head 26, 85 formed with a flaring or curved inner face adapted to rest and pivotally move in the seat 22 between the overhanging portions 23 and 24. A sleeve or tubular member 27, having an annular seat 28, is slipped over the 90 tie rod 25 and passes through the perforation 14 in the flange 13, and upon it the flange is adapted to slide. At its forward end the sleeve is provided with a plurality of aligned openings 29 and 30 adapted to 95 align with an elongated opening or recess 31 formed in the tie rod 25. Between the annular seats 15 and 28 of the flange 13 and the sleeve 27, respectively, and seated thereon, I provide a suitably formed buffer spring 100 E, and upon the threaded rear end 32 of the tie rod I threadingly mount a nut 33, having an elongated hollow internally threaded shank 34 lying within the enlarged cylindrically formed rear end of the sleeve 27, as 105 shown. The nut forms an adjustable abutment for the sleeve and the spring E, and is provided with wings 35 adapted to be struck with a hammer or similar instrument to adjust the nut along the tie rod 25 to vary the 110

compression of the spring or to entirely relieve such compression, as desired. The spring serves to project the coupling head B and maintain it at the limit of its forward movement with the flange 13 normally engaging the rear face 36 of the bracket D, and the rear face of the anchor device 18, as shown particularly in Figure 1. In this manner the coupling head is yieldingly sustained in the normal coupling position and is placed, with its gasket 37, under the desired pressure when mating connectors coupled up in service.

In operation the wings 38 of the coupling head B serve to align the opposing heads and bring their respective gaskets 37 into register. Further movement of the coupling heads will compress the spring E, shifting the body A rearwardly along the sleeve 27 and the tie rod 25 and carrying the flange 13 away from the rear face of the bracket. This movement releases the universal joint formed between the head 26 of the tie rod and the projection or anchor device 18 of the bracket D, whereupon the mated connectors may move universally with respect to their brackets, the universal joint mentioned offering almost no resistance to such movement thereby insuring that the connectors will operate practically as one continuous member with absolutely no relative motion between the faces of their mated heads B. When it is desired to remove a defective gasket 37 from mated coupling heads without first uncoupling the cars, a pin, or other suitable device, such as an ordinary spike nail, 39 is passed downwardly through the aligned holes 29 and 30 nearest the flange 13, the pin passing, of course, through the opening 31, in the tie rod 25. The nut, or abutment 33 is then backed off by striking the wings 35 thereof or applying a wrench thereto, until the retractive action of the spring E is arrested by contact of the pin 39 with the flange 13. The nut is then backed off the tie rod 25 a further extent sufficient to permit the tie rod to be shoved forward in the sleeve 27 until its perforated head 26 occupies the position shown in dotted lines in Figure 3, whereupon the entire connector may be dropped from the bracket D, the defective gasket replaced, and the connector reapplied by retracing the operations described. The construction comprehends means by which the spring E is anchored to the pipe on body A, and by which the tie rod 25, the sleeve 27, and the nut 33 are retained in assembled relation during the removal of the connector from the bracket D and its replacement thereon.

In event the pin 39 becomes lost, and a suitable substitute therefore is not available, the removal of a defective gasket is accomplished by relieving the spring E, on the

mating connectors, of its compression by backing the nut 33 rearwardly on the threaded portion of the tie rod 25. In this manner the tie rod is relieved of tension and may be shifted forward, as above described, 70 and its head 26 disconnected from the projection 18. The reverse of this operation will re-assemble the parts.

It will be noted, especially from Figure 5, that the sleeve 27 and the tie rod 25 are 75 rectangular in cross section for a substantial distance to the rear of the flange 13 and that the fit between the sleeve and the flange 13, and between the body A and the head 26 of the tie rod 25, is such as to prevent excessive independent rotation of these parts and to insure proper relative alignment thereof—see Figures 2 and 5. The opening in the head 26 of the tie rod 25 is, of course, 80 sufficiently large to permit the tie rod to be readily assembled on the projection 18, the overhanging portion 23 of the projection cooperating with the tie rod to support the connector on the bracket D, with the member A free to slide along the sleeve 90 27 against the resistance of the spring E, by which resistance the tie rod is maintained in its seat 22.

What I claim is:

1. In an automatic train pipe connector, the combination with a car coupler, of a coupling head and a support for suspending the head from said coupler, said support comprising a bracket and a spring, which said spring is adapted to be constrained when said coupling head is in the coupled position with a mating head, and means to permit said coupling head to be disconnected from a mating head while said car couplers remain coupled, said means comprising a device to maintain said spring constrained while effecting such disconnection. 105

2. In an automatic train pipe connector, the combination with a car coupler, of a coupling head and a support for suspending the head from said coupler, said support comprising a bracket and a spring, which said spring is adapted to be constrained when said coupling head is in the coupled position with a mating head, and means to permit said coupling head to be disconnected from a mating head and removed from said bracket while said couplers remain coupled, said means comprising a device to maintain said spring constrained while effecting such disconnection and removal. 115

3. In an automatic train pipe connector, the combination of a coupling head, a support therefor comprising a bracket and a spring, and means to permit said head to be disconnected from a mating head while the cars remain coupled, said means comprising a device at the rear of said bracket adapted to arrest the retractive action of said spring. 125 130

4. In an automatic train pipe connector, the combination of a coupling head, a support therefor comprising a bracket and a compression spring, and means to permit 5 said head to be disconnected from a mating head and removed from said bracket while the cars remain coupled, said means comprising a shiftable pivot device and a member to maintain said spring constrained while 10 effecting such disconnection and removal.

5. In an automatic train pipe connector, the combination of a coupling head, a support therefor comprising a bracket and a compression spring, and means to permit 15 said head to be disconnected from a mating head while the cars remain coupled, said means comprising a member engaging one end of said spring and extending towards the other end, a pivot device shiftable relative to said member, and means co-operating with the member to maintain said spring under compression while effecting such disconnection.

6. In an automatic train pipe connector, 25 the combination of a coupling head, a support therefor comprising a bracket, a spring, a device for anchoring said spring to said bracket, and means to permit said head to be removed from said bracket and reassembled thereon without disassembling said spring and said device with respect to said head.

7. In an automatic train pipe connector, 35 the combination of a coupling head, a support therefor comprising a bracket having a projection at its lower end, a device hooked over said projection and having pivotal connection therewith, a member extending rearwardly from said head past said bracket 40 and having an opening through which said device extends, a spring co-operating with this member to project said head, and means to permit said device to be disconnected from said projection without disassembling said spring with respect to said member.

8. In an automatic train pipe connector, 50 the combination of a coupling head, a support therefor comprising a bracket having at its lower end a bearing, a device seated on said bearing for rocking movement thereon, a member extending rearwardly from said head past said bracket and having an opening through which said device extends, a compression spring co-operating with said member to project said head, and means to permit said device to be removed from said bearing without relieving said spring of its retractive action.

60 9. In an automatic train pipe connector, the combination of a coupling head, a support therefor comprising a bracket having a projection at its lower end, a device hooked over said projection and having pivotal connection therewith, a member extending rear-

wardly from said head past said bracket and having an opening through which said device extends, said member being provided also with a projection adapted to engage 70 said bracket to limit the forward movement of said head, an abutment adjustably mounted upon the rear end of said device, a spring between said abutment and one end of said member and acting to project said member and head, a sleeve extending from one end 75 of said spring to the other and relative to which spring said device is shiftable, and means co-operating with said sleeve to permit said device to be disconnected from the projection on said bracket while said spring 80 remains under compression.

10. In an automatic train pipe connector, the combination of a coupling head, a support therefor comprising a bracket having a projection at its lower end, a device hooked over said projection and having pivotal connection therewith, a member extending rearwardly from said head past said bracket and having an opening through which said device extends and being provided also with a 90 projection adapted to engage said bracket to limit the forward movement of said head, an abutment adjustably mounted upon the rear end of said device, a compression spring between said abutment and one end of said 95 member and acting to project said member and head, a sleeve extending from one end of said spring to the other and relative to which said device is shiftable, means co-operating with said sleeve to permit said device to be disconnected from the projection on said bracket without relieving said spring of its compression, and means to prevent excessive rotation of said sleeve during such disconnection.

11. In an automatic train pipe connector, 105 the combination of a coupling head, a support therefor comprising a bracket having a projection at its lower end, a device hooked over said projection and having pivotal connection therewith, a member extending rearwardly from said head past said bracket and having an opening through which said device extends and being provided also with a projection adapted to engage said bracket 110 to limit the forward movement of said head, an abutment adjustably mounted upon the rear end of said device, a spring between said abutment and one end of said member and acting to project said member and head, 115 a part extending from one end of said spring to the other and relative to which said device and said member are shiftable, and means for locking said member against shifting along said part, for the purpose described.

12. In an automatic train pipe connector, 120 the combination of a coupling head, a support therefor comprising a bracket having a bearing at its lower end, a device seated in said bearing for pivotal movement there- 130

on, a member extending rearwardly from said head past said bracket and having an opening through which said device extends and being provided also with a projection adapted to engage said bracket to limit the forward movement of said head, an abutment mounted upon the rear end of said device, a spring between said abutment and one end of said member and acting to project the member, and a sleeve slipped over said device and extending through said spring and relative to which said device and said member are shiftable, said sleeve being provided with an opening aligning the slot in said device, and means extending through said opening and said slot to lock said member against forward movement along said sleeve.

13. In an automatic train pipe connector, 20 the combination of a coupling head, a bracket, a device for supporting said head on said bracket, said device being supported for universal movement on said bracket, a spring associated with said device for yieldingly holding said head in normal coupling 25 position, an abutment for said spring anchored to said device, and means for arresting the retractive action of said spring to permit the removal of said device from said bracket.

14. In an automatic train pipe connector, 30 the combination of a coupling head, a member extending rearwardly therefrom, supporting means for said head and member comprising a bracket and a spring, the spring being seated on said member, and means for locking said spring to said member under compression, said means comprising a device anchored at one end to said spring and at the other end to said member.

15. In an automatic train pipe connector, 35 the combination with a car coupler, of a coupling head and a support for suspending the head from said coupler, said support comprising a bracket and a spring, and

means to permit said coupling head to be disconnected from a mating head while said coupler remains coupled to a companion coupler, said means comprising a member extending rearwardly from said head past 50 said bracket, and a device to maintain said spring under compression while effecting such disconnection.

16. In an automatic train pipe connector for cars, the combination of a coupling head, 55 a support therefor comprising a bracket and a spring, and means to permit said head to be disconnected from a mating head while the cars remain coupled, said means comprising a device for maintaining said spring under 60 compression while effecting such disconnection.

17. In an automatic train pipe connector for cars, the combination of a coupling head, 65 a support therefor comprising a bracket and a spring, and means to permit said head to be disconnected from a mating head while the cars equipped therewith remain coupled, said means comprising mechanism pivotally supported by said bracket and serving to 70 arrest the retractive action of said spring whereby said bracket is freed from the pressure of said spring during such disconnection.

18. In an automatic train pipe connector, 75 the combination of a coupling head, a support therefor comprising a bracket and a spring, and means to permit said head to be disconnected from a mating head while the cars equipped therewith remain coupled, 80 said means comprising a member extending from said head past said bracket into engagement with said spring, and means pivotally supported on said bracket for arresting the retractive action of said spring to 85 free the bracket of the pressure of the spring during such disconnection.

In testimony whereof I hereunto affix my signature.

JOSEPH ROBINSON.
